UNITED STATES PATENT OFFICE.

JOHN C. HEINRITZ AND JAMES WATSON MCCUEN, OF BALTIMORE,
MARYLAND.

INCANDESCENT VAPOR-BURNER.

SPECIFICATION forming part of Letters Patent No. 671,884, dated April 9, 1901.

Application filed November 23, 1900. Serial No. 37,508. (No model.)

To all whom it may concern:

Be it known that we, JOHN C. HEINRITZ and JAMES WATSON MCCUEN, citizens of the United States, residing at Baltimore, State of Maryland, have invented certain new and useful Improvements in Incandescent Vapor-Burners, of which the following is a specification.

For incandescent vapor-burners wherein the vapor is generated as it is consumed by the heat of the burner-flame we have designed a novel construction of burner-head whereby the vaporizing-heat is furnished and maintained, and the precise improvement therein will be set out in the claims hereto appended, in connection with the accompanying drawings, in which—

Figure 1 is a vertical section of a vapor-lamp embodying our improvement. Fig. 2 is a like section taken through the vapor-supply pipe. Fig. 3 is a vertical section showing the solid burner-head and the vapor-mixing tube. Fig. 4 is a horizontal section of the solid burner-head. Fig. 5 is a vertical section of the same.

The several sectional views show a central chamber in the solid burner-head and its communication with the mixing-tube for supplying the jet-flames.

A solid head 1 comprises the burner-body and has the burner-forming part 2, within the chamber 3 of which the combustion of the vapor takes place. The burner has the usual foraminous cap, through which the combustible vapor passes to the mantle. The solid burner-head has a central bore which passes through and within which the upper open end of the mixing-tube 6 is shrunk and from which it depends. At one side of the mixing-tube the burner-head has a bore opening on its under side and within which the vapor-supply pipe 15 is secured and from which it depends and terminates in a valved opening centrally with and below the vapor-mixing tube. A bore is made in one side of the solid burner-head near its bottom, into which is secured the oil-supply 11, which is supplied from an elevated reservoir (not shown) in the usual manner. The provision for rendering effective and maintaining the flame is formed

and supply the vapor from the oil-supply pipe. The generator for the vapor is formed by the duct 12, leading from the oil-supply pipe 11 to the top part of the head, thence by 55 the horizontal duct 13, extending across the head just beneath its top surface, and by the duct 14, terminating in the open end of the vapor-supply pipe, Fig. 2. Within the center of the head is an annular chamber 5 around 60 the vapor-mixing tube, which by perforations 6' in its sides has communication with said chamber as in Fig. 5. From this inclosed central chamber extend ducts 8, Fig. 4, which open at the top of the solid head. Overhanging the openings 9 of these vapor-jet ducts is a rim 10, formed around the burner-chamber 3, so that when the vapor-jets issuing from these ducts are ignited the flame therefrom will on striking the rim be deflected down upon 70 the top of the solid head, heating it and the generator-ducts therein. Within and through these duct-heads 12 and 13 the oil passes from the supply-pipe 11 and is vaporized by the heat of the burner-head.

The ordinary needle-valve 16 controls the flow of the vapor into the mixing-tube from which the burner is supplied.

A shield 4 depends from the burner-head, incloses the valve-controlled vapor-supply pipe and the mixing-tube, and has perforations 17 for the admission of air for mixing with the vapor. The bottom of this shield may also be perforated. A perforated curb 18 19 incloses the solid burner-head and its 85 jet-flames as a housing protection for the jet-flames and for the heated head and for affording ventilation to that portion of the mantle which incloses the burner. This curb supports the mounting-stem 20 for the mantle. 90

The initial heating of the solid burner-head may be by torch for starting the vaporization of the oil in the ducts and for filling the valved vapor-supplying pipe when the valve is opened, and the vapor passing out is mixed 95 with air in the mixing-tube, from which it passes to the burner.

The provision of the chamber inclosed in the solid head and having communication with the mixing-tube by the holes 6' in the 100 walls of the latter thereby makes said chamber a reservoir always filled with vapor and

uniformly supplies the jet-flames, whereby the degree of heat is rendered constantly effective for vaporizing the oil to produce a sufficient and constant supply of vapor and 5 to supply it in a highly-heated condition to the mantle. In a burner of this kind the important matter is to maintain a constantly-uniform heat in order to produce a constantly-uniform volume of vapor and therefore 10 by a constantly-uniform or steady flame to heat the mantle to a uniform incandescence. For this the solid burner-head once heated keeps its heat to a high degree.

Obviously the upward draft and pressure of 15 the combustible mixture within and through the mixing-tube will cause a constant flow of the vapor through the openings 6' into the inclosed chamber 5, and thus constantly supply and force the vapor from this chamber up 20 through the ducts in the solid head to supply the jet-flames, while the solidity of the head and the fixing of the mixing-tube, the vapor-supply pipe, and the oil-supply pipe directly 25 therein gives efficiency for maintaining a high vaporizing heat in the head.

To facilitate the initial heating of the solid burner-head by the torch, the bottom of the shield may be made removable and the bottom of the burner-head formed with a central cavity, so as to concentrate the heat. A 30 convenient way of forming the holes in the mixing-tube, so that they will register with the inclosed vapor-chamber, is to drill a hole 7

through the burner-head, so as to pass through the center chamber and the walls of the mixing-tube, and then plug the bore at the walls of the head, as in Fig. 3, the chamber having been reamed out before the mixing-tube is secured in place.

We claim—

1. In a vapor-burner, a burner-head having a central opening, a recessed chamber, a rim, ducts leading from the chamber having their openings adjacent the rim, and vaporizing-passages, a mixing-tube arranged in the central opening of the burner-head, passing through and closing the chamber and having perforations leading into said chamber whereby a reservoir is formed around the walls of the mixing-tube for supplying said ducts. 40 45

2. In a vapor-burner, a burner-head having a central opening, a recessed chamber, a rim, ducts leading from the chamber and terminating beneath the rim, and vaporizing-passages, a mixing-tube arranged in the central opening of the burner and closing the chamber said tube having wall-perforations below its upper end leading into said chamber 55 around the walls of the mixing-tube.

In testimony whereof we affix our signatures in presence of two witnesses.

JOHN C. HEINRITZ.

JAMES WATSON MCCUEN.
